UNITED STATES PATENT OFFICE

159,065

SPECTACLE FRAME

Simon Hochland, New York, N. Y.

Application March 8, 1949, Serial No. 1,275

Term of patent 3½ years

(Cl. D57—1)

To all whom it may concern:

Be it known that I, Simon Hochland, a citizen of Germany, residing at New York, in the county and State of New York, have invented a new, original, and ornamental Design for a Spectacle Frame, of which the following is the specification, reference being had to the accompanying drawings, forming part thereof.

Fig. 1 is a side elevational view of a spectacle frame, showing my new design, the temple on the opposite side of the frame being ornamented on the outside in a manner as herein shown; and

Fig. 2 is a top plan view thereof.

The essential features of my design for a spectacle frame reside in the type of ornamentation and its specific placement on the outside of the temples in a manner as illustrated.

I claim:

The ornamental design for a spectacle frame, as shown and described.

SIMON HOCHLAND.
